CONTACT FOR ELECTRICAL APPARATUS

Roy Wilkins, San Francisco, Calif., assignor to
K. P. F. Electric Company, San Francisco,
Calif.

Application September 8, 1936, Serial No. 99,744

7 Claims. (Cl. 200—166)

The present invention relates to an electrical apparatus, and more particularly to an improved contact surface and method of forming same upon the engaging parts of copper current conducting members of electrical apparatus and circuits.

An object of the invention is to provide an improved contact surface for the engaging parts of current carrying conductors which will have improved non-heating and current carrying characteristics.

Another object of the invention is to provide a novel form of contacting surface for the engaging parts of current conducting members, which is of a non-insulating film forming character.

Another object of the invention is to provide a new and novel method of applying silver and like metals to the contact forming surfaces of electrical switch contacts.

It is well known that under normally elevated temperatures copper tends to oxidize and thus form an insulating film upon the surface thereof. This oxidation upon the contacting surfaces of copper conductors also causes increased heating at the contact when heavy currents are transmitted therethrough, and this heating in turn accelerates the process of oxidation and may eventually result in a temperature sufficiently high to anneal the copper parts, and in extreme cases pit and otherwise physically damage the contacting surfaces. To overcome this disadvantage many manufacturers of switches have resorted to a plating of the cooperating contact surfaces of the switch with silver, both by the electroplating method and in accordance with the so-called "Schoup spray" process; while others have resorted to the brazing of a sheet of silver upon the cooperating contact forming surfaces of the switch contacts. While these courses of procedure have been found to overcome the objections due to oxidation of the copper, as suggested above, resort to these methods complicates the manufacturing operations and greatly increases the cost of the apparatus. It is therefore a further object of the present invention to provide a new and novel method for applying a non-oxidizing contact surface to the cooperating surfaces of the current conducting members which will overcome the above difficulties, and at the same time provide a simple, practical and less expensive construction.

Other objects and advantages of the invention will be in part hereinafter pointed out and in part evident to those skilled in the art as the de-

scription thereof, taken in connection with the accompanying drawing, proceeds.

In the drawing, wherein there is shown by way of illustration and not of limitation, preferred embodiments of the invention:

Figure 1 is a fragmentary side view showing the cooperating contact forming members of a high-voltage disconnecting switch.

Figure 2 is a view showing the position of the blade and the cooperating contact clips of the switch of Figure 1, when the switch blade is in its circuit closed position.

Figure 3 is a perspective view showing the details of construction of the switch clip illustrated in Figures 1 and 2 of the drawing.

Figure 4 is a perspective view showing the details of the switch blade illustrated in Figures 1 and 2 of the drawing.

Figure 5 is a perspective view showing the manner of applying the invention to a switch blade of the type illustrated in Figure 4.

Figure 6 is a fragmentary sectional view taken along lines VI—VI of Figure 5, looking in direction of arrows, and

Figure 7 is a fragmentary view showing an application of the invention to the contacting parts of a bus bar system.

Reference is now made to Figure 1 of the drawing, wherein, for the purpose of this description, the invention is shown as applied to a switch blade and the cooperating clips of an air break switch of the so-called disconnecting type. As here shown, the numeral 10 designates a switch blade which is carried by a suitable supporting member upon the end of a current conducting switch arm 12. Cooperating with the blade 10 there are three sets of opposed blade engaging clips which are mounted upon a supporting member 14 carried at the end of a second current conducting switch arm 15. The switch arms 12 and 15 are pivoted at their outer ends so that the switch blade 10 and the blade engaging clips 13 move into engagement along arcs of circles determined by the length of the switch arms 12 and 15.

As is better shown in Figure 2 of the drawing, the switch clip supporting member 14 has oppositely disposed side members that form box-like enclosures for the opposed contact clips 13, and between which the switch blade 10 may freely move into engagement between the blade engaging clips 13. These side members, designated by the numeral 16, are also shown as having blade guiding extensions 17. The blade engaging clips 13 are yieldingly supported within the box-like members 16 by means of pressure exerting springs 55

18 in a conventional manner, and extending from the back of each of the clips 13 there is a flexible current conducting pigtail 19 which serves to conduct the current from the clips 13 to their supporting member 14 and to the current conducting switch arm 15.

As shown in Figure 3 of the drawing, each of the contact clips 13 has a pair of longitudinally extending raised contact forming surfaces 20 which are preferably of silver, and as shown in Figure 4 of the drawing, the switch blade 10 is shown as having spaced longitudinally extending raised contact forming members 21 extending longitudinally along each side thereof. The contact forming members 20 upon the clips 13 and the members 21 upon the switch blade 10 are preferably formed by securing an outwardly projecting strip of silver upon the surface of the clips and blade in a novel manner to be now described.

The method of applying the contact forming members 20 to the clips 13 and the contact forming members 21 to the switch blade 10 is clearly illustrated in Figures 5 and 6 of the drawing. As here shown, the switch blade 10 is provided with spaced and oppositely disposed grooves 22 into which a strip of silver or other non-insulating film forming metal 23 may be disposed. The grooves 22 may be straight-sided or undercut and are of a depth less than the thickness of the metal strip 23, so that the strips 23 will extend above the surfaces of the blade 10. When the blade 10 has been grooved as above, a strip of the contact forming metal 23 having a proper contour and thickness is laid into one of the grooves 22 and then by the application of pressure through a roller or other tool 24 the metal 23 is pressed with a metal flowing pressure into intimate contact with the sides and bottom of the grooves 22, and at the same time the sides of the grooves 22 are rolled inwardly and into firm overlapping engagement with the sides of the contact forming strip 23. In this operation, as is better illustrated in Figure 6 of the drawing, the contact surface forming strip 23 is slightly deformed by the roller 24, and the metal thereof is caused to flow cold into intimate air excluding contact with the bottom and sides of the grooves 22, while at the same time the inner rolled sides of the groove 22 will firmly hold the metal strip 23 in this condition with its outer surface extending above the adjacent surfaces of the blade 10.

The application of the contact forming member 20 to the clips 13 is carried out in a manner similar to that above described in connection with the formation of the switch blade 10. However, as shown in Figure 3 of the drawing, the grooves for the metal strips 20 do not extend around the curved ends of the clips 13, and therefore the contact forming members 20 are finished with a rounded end as at 25, to facilitate movement of the contact forming members 21 thereover, when the switch blade 10 moves into its circuit closing position between the clips 13.

While the invention has been described above as applied to an air break switch, it is to be understood that the invention is equally applicable to switches having oil immersed contacts.

In Figure 7 of the drawing, there is illustrated another use to which the invention is applicable. As here shown, the invention is applied to a bus bar system by securing contact forming strips 26 75 of silver, in the manner above described, upon a

bus bar connection 27 which engages a bus bar 28. As here shown, the bus bar connection 27 is secured with the contact forming members 26 in high pressure engagement with the bus 28 by means of conventional triangular clamping plates 29 and bolts 30, in accordance with standard practice.

While silver has been above referred to as the preferred metal for the contact forming strips 20 and 21, it is to be understood that this term 10 is to include alloys of silver and other low resistance metals having the desired characteristics of silver. It is to be also understood that the contact forming strips 20 and 21 need not initially have a half-round configuration, as it is conceivable that metal strips having other configurations may be rolled and pressed into the grooves 22 to produce a contact surface in accordance with the invention.

In conclusion it may be added that a half-round sterling silver strip of 986 fineness, having a diameter of three-sixteenths inch ($\frac{3}{16}$ "), and projecting above the surface of the switch blade approximately three thirty-seconds inch ($\frac{3}{32}$ "), provides a practical and highly efficient contact. 25 A switch constructed as illustrated in Figure 1 of the drawing, and employing contact forming strips of the above dimensions has been tested under a continuous load of 800 amperes alternating current with a constant 30° rise, which is 30 within the permissible limit under A. I. E. E. standards.

While I have, for the sake of clearness and in order to disclose the invention so that the same can be readily understood, described and illustrated a specific arrangement, I desire to have it understood that this invention is not limited to the specific means disclosed, but may be embodied in other ways that will suggest themselves to persons skilled in the art. One such variation is that when the groove 22 is undercut as suggested, the sides of the groove need not be rolled in, as the silver, under this condition, will be flowed by pressure under the overhanging sides of the groove. It is believed that this invention is new and it is desired to claim it so that all such changes as come within the scope of the appended claims are to be considered as part of this invention.

Having thus described my invention, what I 50 claim and desire to secure by Letters Patent is—

1. In an electrical switch of the knife blade type, the combination of a blade-like member having longitudinally extending and oppositely disposed non-oxidizing contact surface forming members secured upon each side thereof, and co-operating blade engaging clips between which said blade-like member is adapted to move having transversely extending non-oxidizing contact surface forming members secured upon the blade 60 engaging sides thereof, the contact surface forming members upon said blade-like member and the contact surface forming members upon said clips being half round in cross section and secured in place by cold pressing same into grooves 65 cut in the surfaces of their respective supporting blade and clips.

2. In an electrical switch of the knife blade type, the combination of a blade-like member having raised contact forming members of a 70 non-insulating film forming metal inlaid on the opposite surfaces thereof, and co-operating blade engaging clips between which said blade-like member is adapted to move also having raised contact forming members of a non-insulating 75

film forming metal inlaid on the surfaces thereof, the raised non-insulating film forming members upon said blade-like member and upon said clips being half round in cross section and arranged to normally extend transverse to each other with their rounded sides engaging when the blade-like member is in its circuit closing position between the cooperating blade engaging clips.

10 3. In an electrical switch of the knife blade type, the combination of a blade-like member having parallel extending and oppositely disposed contact surface forming members of silver secured thereupon, and cooperating blade engaging

15 clips between which said blade is adapted to move also having spaced contact surface forming members of silver secured upon the blade engaging sides thereof, said silver contact surface forming members upon said blade-like member and upon said cooperating blade engaging clips being half round in cross section and arranged to normally extend transverse to each other with their rounded surfaces engaging when the switch blade is in its circuit closing position between

20 said clips.

25 4. In a circuit interrupter, the combination of a blade-like member of copper having a raised longitudinally extending contact forming surface of silver, said surface of silver being formed by

30 grooving the surface of said blade and cold rolling a silver strip into said groove under pressure, a pair of full floating and opposed switch blade engaging clips also having a raised contacting surface of silver extending longitudinally thereof

35 and normally transverse to the raised silver surface upon said blade when the circuit interrupter is closed, the raised silver surface upon said opposed clips being also formed by cold rolling a strip of silver under pressure into a groove in

the surface of said clips, and pressure producing means cooperating with said clips to produce a uniform contact pressure between the transversely disposed silver contact surfaces upon said blade and clips.

5. An improved contact surface construction for electrical apparatus comprising cooperating copper conductors each having spaced parallel and raised silver surfaces formed by cold pressing a strip of silver into grooves cut in the adjacent sides thereof, the disposition of said raised contact surfaces upon said current conducting members being such that when said members are connected together in current conducting relation said silver contact surfaces upon the respective conductors will lie transverse to each other.

6. An improved blade for electrical circuit interrupters comprising a blade-like member constructed of copper having a plurality of longitudinally extending grooves cut in the opposite sides thereof, and having raised silver contact making surfaces formed by cold flowing a strip of silver into intimate engagement with the bottom and sides of said grooves.

7. In a contact engaging clip for an electrical switch, the combination of a pair of oppositely disposed contact forming members having raised silver contact surfaces extending in the line of movement of the cooperating contact, said raised silver contact surfaces being formed by cold pressing a strip of silver into a groove cut in the face of said contact members, and a pressure producing means disposed in cooperating relation with said contact members to produce a high contact pressure between said silver contact surfaces and a cooperating circuit completing member of the switch.

ROY WILKINS.
